US0D1070032S

(12) **United States Design Patent** (10) **Patent No.:** **US D1,070,032 S**
(45) **Date of Patent:** **** Apr. 8, 2025**

(54) **GASKET**

- (71) Applicant: **BruMate, Inc.**, Dover, DE (US)
(72) Inventor: **Dylan M. Jacob**, Denver, CO (US)
(73) Assignee: **Brumate, Inc.**, Denver, CO (US)
(**) Term: **15 Years**
(21) Appl. No.: **29/814,865**
(22) Filed: **Nov. 9, 2021**

amazon.com/dp/B07H8N6SXF/, pp. 1-10, accessed on Oct. 28, 2022.

Primary Examiner — Keith J Wilson

Assistant Examiner — Assam Y. Fittahy

(74) *Attorney, Agent, or Firm* — Shook, Hardy & Bacon L.L.P.

(57) **CLAIM**

The ornamental design for a gasket, as shown and described.

DESCRIPTION

- (62) Division of application No. 29/688,948, filed on Apr. 25, 2019, now Pat. No. Des. 935,576.
(51) **LOC (15) Cl.** **23-01**
(52) **U.S. Cl.**
USPC **D23/269**
